DECORATIVE PANEL FOR USE ABOVE A BACK BAR

Leon H. Richman, Long Beach, and James Michael Clayton, Costa Mesa, Calif., assignors to Baskin-Robbins Ice Cream Co., Burbank, Calif.

Original design application Mar. 28, 1974, Ser. No. 455,557. Divided and this application May 22, 1975, Ser. No. 580,011

Term of patent 14 years

Int. Cl. D6—06

U.S. Cl. D6—193

Fig. 1

Fig. 2

Fig. 3

Fig. 4

Fig. 5

Fig. 6

FIG. 1 is a front elevational view of a decorative panel for use above a back bar showing our new design;

FIG. 2 is a left side elevational view;

FIG. 3 is a right side elevational view;

FIG. 4 is a top plan view;

FIG. 5 is a bottom plan view; and

FIG. 6 is a rear elevational view.

This is a divisional application of Ser. No. 455,557, filed Mar. 28, 1974.

We claim:

The ornamental design for a decorative panel for use above a back bar, substantially as shown and described.
